UNITED STATES PATENT OFFICE.

ALBERT BOLLER, OF WETZIKON, SWITZERLAND.

YARN.

Application filed May 17, 1926, Serial No. 109,782, and in Switzerland October 17, 1925.

It has hitherto not been possible to manufacture knitted fabrics, which term is intended to include tricot fabrics, from tightly twisted yarns, such as crêpe twist, which are 5 extensively used in weaving, since knitted fabrics have no binding member such as is provided in weaving by the warp.

The knitted fabric according to the present invention consists of highly twisted 10 yarn and is bound with a loosely twisted thread.

The elasticity which is positively increased by the hard twist gives to the knitted fabric according to the present invention 15 greater durability than possessed by the knitted fabrics made in the usual manner with ordinary yarns and the fabrics so made will conform closely to the shape of the body. The knitted fabric according to the 20 present invention has the appearance of woven crêpe materials and the binding thread imparts to it a velvet-like lustre, which cannot be obtained with the crêpe twist having a hard twist without the binding thread.

The hard twist yarns used may be of silk crêpe, schappe silk crêpe, artificial silk crêpe, wool crêpe, cotton crêpe and the like, while the loose may consist of the same thread 30 material as the hard twist thread or of some other material.

The most suitable articles to be made from the knitted fabric described above are for instance, stockings, dresses, underclothing, gloves and the like.

In the enlarged view shown in the accompanying drawing, 1 and 2 are the threads which are highly twisted in opposite directions and are made, for instance, of crêpe yarn, and 3 is a loosely twisted thread, for 40 instance, of silk, wool, or other suitable material, which is wrapped around the threads 1 and 2 and binds them together.

This combination yarn is worked up in the ordinary way on the knitting machine, 45 care being taken for effectively damping the yarn in unwinding from the bobbin, in order that the same shall not become kinked and be drawn off in a stretched condition by the needles of the knitting machine and 50 the tensioning device.

What I claim is:—

1. A yarn for knitted fabrics consisting of a hard twist yarn and a loosely twisted thread, said thread being helically wound 55 around said yarn.

2. A yarn for knitted fabrics consisting of a hard twist crêpe yarn and a loosely twisted thread, said thread being helically wound around said yarn.

3. A yarn for knitted fabrics consisting of two hard twist yarns, said yarns being twisted in opposite directions, and a loosely twisted thread, said thread being helically wound around both of said yarns.

In testimony whereof I have affixed my signature.

ALBERT BOLLER.
